(57) CLAIM

I claim the ornamental design for a golf green cigar humidor, as shown and described.

DESCRIPTION

A golf green cigar humidor with a lid that has the appearance of a golf green, including ornamental flag, to be used for ornamentation and to store cigars.

FIG. 1 is a top perspective view of the golf green cigar humidor, the broken line disclosure of the logo and hinges is for illustrative purposes only and forms no part of the claimed design.

FIG. 2 is a right side elevation view thereof.

FIG. 3 is a left side elevation view thereof.

FIG. 4 is a top plan view thereof.

FIG. 5 is a bottom plan view thereof.

FIG. 6 is a rear side elevation view thereof.

FIG. 7 is a front side elevation view thereof.

FIG. 8 is a top perspective view of the second embodiment of the golf green cigar humidor, the broken line disclosure of the hinges is for illustrative purposes only and forms no part of the claimed design.

FIG. 9 is a right side elevation view thereof.

FIG. 10 is a left side elevation view thereof.

FIG. 11 is a top plan view thereof.

FIG. 12 is a bottom plan view thereof.

FIG. 13 is a rear side elevation view thereof; and,

FIG. 14 is a front side elevation view thereof.
